UNITED STATES PATENT OFFICE.

JAMES W. SCULLY, OF HYDE PARK, MASSACHUSETTS.

SUSPENSION DEVICE FOR TROLLEY-WIRES.

SPECIFICATION forming part of Letters Patent No. 650,814, dated May 29, 1900.

Application filed February 5, 1900. Serial No. 3,922. (No model.)

To all whom it may concern:

Be it known that I, JAMES W. SCULLY, a citizen of the United States, residing at Hyde Park, in the county of Norfolk, State of Massachusetts, have invented a certain new and useful Improvement in Suspension Devices for Trolley-Wires, of which the following is a specification, reference being had therein to the accompanying drawings.

10 My invention has for its object to provide an improved suspension device for trolley-wires or conductors for electric railways or the like.

15 The invention is fully set forth in the following description, reference being had to the accompanying drawings, and the novel features thereof being pointed out and clearly defined in the claims at the close of this specification.

20 In the drawings, Figure 1 is a side elevation of a suspension device embodying my invention, a small portion of the upper member thereof being broken away to show the shoulder which is formed on the lower member.

25 Fig. 2 is a section on the line 2 2 of Fig. 1.

In suspending a trolley-wire or conductor it is usual to employ what is termed an "ear," the upper portion of which ordinarily is provided with a threaded socket, by means of which the ear is secured to a suitable supporting device. The lower edge of the ear is grooved to inclose or partially inclose the trolley-wire, and the intermediate portion or body of the ear is usually a relatively-thin web of metal. The lips which form the sides of the groove at the lower edge of the ear are thin, so that when the trolley-wire is placed in the groove these lips may be bent in over the wire, so as to embrace it and hold it firmly in place. The passage of the trolley along the wire wears away the edges of the lips which hold the wire in place and serve to secure it to the ear, and when they are worn away the ear requires to be removed and replaced. Ears that are thus discarded after use because of the wearing away of the lips which embrace the trolley-wire are otherwise as good as new, the other portions thereof not being subjected to wear. To replace the ears that are thus worn is a source of considerable expense. By the employment of my invention hereinafter set forth a considerable sav-

ing is effected, since substantially only that portion of the ear which is in contact with the trolley-wire and which is subjected to wear by the trolley requires to be replaced, the other portions of the ear which are not subjected to wear being retained, thus economizing in the cost of material, in the time required to make the repairs, and at the same time facilitating the work of repair by lessening the weight and bulk of the parts which require to be replaced.

My invention is simple and will be readily understood from the following description.

Referring to the drawings, the top or upper member of the ear is shown at A, the threaded socket by means of which the ear is secured to its support being shown at B. The web or body of the said top or upper member of the ear is shown at C. The lower edge of the web or body C is provided lengthwise with a groove D of the shape shown in Fig. 2, the intermediate portion of the groove between the bottom and the mouth thereof being contracted, as shown at 2. The said groove, in other words, has an inwardly-expanded portion. That portion of the ear which is secured directly to the trolley-wire is shown at E, and consists of a grooved strip that is provided lengthwise thereof with a web 3, which web may extend throughout the whole or a portion of the length of the part E. The said web 3 is formed of a shape in cross-section to fit the groove D in the flange C, as shown, Fig. 2, thus permitting the said web 3 to be slid endwise into the groove D, as will be clear. As will be perceived, the grooved strip extends lengthwise of the body portion. The shape of the groove D and web 3, respectively, is such as to form a longitudinal interlocking joint between the two members of the ear or supporting device, as will be apparent. On the web 3 a shoulder 4 is formed, the said shoulder being at one end thereof. The web 3 is slid into the groove D until the shoulder 4 bears against the end of the web C. This prevents further relative movement of the parts in one direction. A hole 5 is shown formed transversely through the web 3 at the other end of the groove D, and a cotter-pin 6 is inserted in the said hole. This forms a convenient means of locking the parts from relative movement in the other direction, and

consequently the parts are held from becoming separated. In brief, the parts C and E are prevented from movement relatively to each other and from becoming displaced by 5 said shoulder 4 at one end and the cotter-pin 6 at the other end. When the part E which incloses and secures the trolley-wire is worn to such an extent as to require its replacement, it is necessary only to remove the cotter-pin 6, slide the upper portion C of the ear off the flange 3 on the lower portion E, and detach the lower part from the wire. The 10 said lower part can then be replaced by a new part of like construction, which can be easily 15 slid into place in the groove of the upper part and properly secured to the trolley-wire.

I do not desire to limit my invention to suspension devices of the form shown and hereinabove described or to the precise construction 20 of the parts, since my invention may be readily adapted to various forms of suspension devices and may be variously embodied in practice.

What I claim is—

25 1. A suspension device for trolley-wires, comprising essentially a grooved strip for attachment to the wire and a body portion along which said strip extends and to which it is connected by a separable joint, substantially 30 as described.

2. A suspension device for trolley-wires, comprising essentially a grooved strip for attachment to the wire and a body portion along which said strip extends, the said parts con-

nected by a longitudinal slip-joint, substantially as described. 35

3. A suspension device for trolley-wires comprising a part adapted to receive and hold the trolley-wire, another part adapted to be secured to a supporting device, a groove inwardly expanded in cross-section in one of said portions, and a corresponding web or projection on the other of said portions, whereby the said portions may be detachably secured together, substantially as described. 40

4. A suspension device for trolley-wires comprising a part E for attachment to the trolley-wire, a part C for attachment to the supporting means, an inwardly expanded groove in one of said parts and a corresponding projection on the other of said parts, and means for preventing displacement and detachment of the said parts in the line of the joint when they are secured together, substantially as described. 45

5. A supporting device for trolley-wires comprising a suspending device and a portion for connection with the wire, separably combined by an interlocking longitudinal joint, and a locking device to prevent movement of the parts in the line of the said joint, substantially as described. 50

In testimony whereof I affix my signature in presence of two witnesses.

JAMES W. SCULLY.
